OUTDOOR DISPLAY CASE FOR JEWELRY AND OTHER MERCHANDISE

Leonard W. Beck, 240 Wroe Ave., Dayton, Ohio

Filed Nov. 5, 1959, Ser. No. 58,290

Term of patent 14 years

(Cl. D80—11)

FIG. 1

FIG. 3

FIG. 1 is a perspective view taken from the top of an outdoor display for jewelry and other merchandise embodying my new design.

FIG. 2 is a top plan view thereof; and

FIG. 3 is a bottom plan view thereof.

I claim:

The ornamental design for an outdoor display case for jewelry and other merchandise, as shown.
